HIGH PRESSURE CONTAINER

Percy C. Avery, Milwaukee, Wis., assignor to
Avery Products Co., Inc., Milwaukee, Wis.

Application April 30, 1934, Serial No. 723,222

5 Claims. (Cl. 229—3)

My present invention relates to high pressure containers adapted for general use, but particularly to the class of portable containers employed for storing, transporting and dispensing fluids under high pressure, for which purpose my invention has been primarily designed.

The invention resides in a high pressure cylindrical container preferably of seamless pressed steel or drawn steel tubular construction having the bottom end-enclosing head integrally formed therewith and having the top end closed by means of the herein designated "combination spud" which may be either electrically welded or removably bolted on to the container.

The primary object of the invention is the provision of said so-called "combination spud" in operative combination with cylindrical containers designed for holding, shipping and dispensing fluids under high pressure, said "combination spud" being provided with a discharge outlet duct, the opening and closing of which is manually regulated and controlled by means of a pair of specially designed valves herein termed the main valve M and the reserve valve R. The main valve M is designed to permit gas to be withdrawn from the container until the pressure thereof falls to say, for example, 150 pounds,—as will hereinafter be explained,—when further gas may be withdrawn only by opening the reserve valve R, the object being to provide warning to the user that the container is about to become exhausted of its gas contents, so that he may order a new or fully charged container from his distributor to replenish his supply on hand before same is exhausted. Further objects of the invention will appear from the following description when read in connection with the accompanying drawings which show illustrative embodiments of the invention, and in which:—

Figure 1 is a front view, largely in vertical section, showing my improved high pressure fluid storage container in its preferred form, showing the "combination spud" or top head, removably bolted to the container.

Figure 2 is an enlarged plan view of the device shown in Figure 1.

Figure 3 is vertical section, drawn on the lines 3—3 of Figure 2, of the preferred form of the so-called "combination spud" or top-head of my improved high pressure container, the container being broken away but showing the upper end portion thereof in operative bolted connection and also in vertical section.

Figure 4 is a vertical section of a safety blow-off plug, drawn on the lines 4—4 of Figure 2.

Figure 5 is a front view of a modified form of my improved high pressure container, over that shown in Figures 1, 2 and 3, showing the "combination spud" or top head electrically welded to the container.

Figure 6 is an enlarged plan view of the device shown in Figure 5.

Figure 7 is a vertical section, drawn on the lines 7—7 of Figure 6, showing a modified form of the so-called "combination spud" or top-head of my improved high pressure container, the container being broken away but showing the upper end portion thereof in operative welded connection and also in vertical section, and

Figure 8 is a vertical section, of a safety blow-off or fuse plug, drawn on the lines 8—8 of Figure 6.

In the drawings, like parts are identified by similar reference characters throughout the several views.

Referring to Figures 1 to 4 inclusive of the drawings, the numeral 10 generally designates my improved high pressure container which may be used for storing, shipping and dispensing various fluids under relatively high pressure, but 25 the same is particularly designed to store therein a cylindrical block 11, or a plurality of cylindrical blocks 11, 11 of so-called "dry ice" or solidified carbon dioxide gas and in addition a bag or cartridge 12, of activated carbon charcoal,—for 30 a purpose which will hereinafter be disclosed,—said "dry ice" 11 and said cartridge or bag 12, of carbon charcoal 12' being installed in the cylindrical container 10, through a removable "combination spud" or top head 13.

The container 10 is preferably formed of steel boiler tubing, having the bottom end head 14, closed in by the hot-metal spinning process. A plurality of specially formed bolts 15 are electrically welded in suitable spaced relation around 40 the upper end 16 of said container 10. The said "combination spud" or top-head 13 is preferably made of close-grained drop-forged steel and is provided with a plurality of suitably spaced bolt holes 17, 17 adapted to fit and receive the said 45 bolts 15, respectively. The "combination spud" 13 is tightly joined to the top end of the container 10 through the connecting bolts 15 and nuts 18 and to ensure a tight joint at the union 19 thereof, the spud 13 has an annular channel-shaped 50 groove 20 formed therein on its lower side 21, adapted to nicely receive and fit the upper annular edge 22 of the container 10, an annular gasket 23, preferably formed of gasket sheet rubber packing, is interposed in the union 19 to ensure 55

a perfect gas-tight joint thereat. To ensure against unauthorized removal of the nuts 18, on the bolts 15, each bolt preferably has a small hole 24, drilled laterally through it near its top end at 5 a point just above the top face of its respective nut and a wire seal 25 is preferably passed laterally around through all of the bolts 15 and its ends are twisted together and sealed as by means of the usual lead seal 26. Obviously, each bolt 15 10 and its nut 18 may be sealed separately by each bolt having an individual locking wire 25' and a separate lead seal 26' therefor in sealing connection. The spud 13 is further provided with an excessive pressure-relief blow-off seal 27, preferably 15 comprising a copper disc of predetermined thickness and diameter seated against an annular seat 28, formed therefor in a bore 29 of the spud 13, and held in sealed engagement therewith as by means of the set-screw 30 which is screw-threaded 20 in the bore 29. The set-screw 30 has a duct 31, longitudinally therein and the spud 13 has another aligned duct 32 arranged to exhaust the confined gas in the container 10 when the seal 27 is ruptured due to excessive temperature or 25 pressure of the confined gas.

The spud 13 has a laterally disposed duct 33, connecting the container 10 with a pipe nipple 34 when one or more controlling valves in operative connection with said duct 33 are opened. The 30 pipe-nipple 34 has screw-threaded connection in the spud 13 laterally thereof. A screw-cap 35 normally closes the free end of said pipe-nipple 34 to prevent leakage of the stored gas in container 10 during shipment or during the time of disuse 35 thereof.

A pair of valves, generally designated by the letters M and R, are of identical construction,—with but one exception which will be hereinafter described,—and are employed to regulate and control the passage of the gas stored in the container 10 through duct 33 and nipple 34 in operative pipe connection not shown, to the usual beer kegs, or other containers, devices and apparatus for which high pressure gas containers are now widely used.

The said valves M and R are formed and installed in the spud 13 whereby the usual protecting valve-cap (not shown) is dispensed with. Each of the valves M and R is preferably constructed as follows:

50 36 is a cylindrical reciprocable valve vertically installed in suitable bores within said spud 13 comprising a valve-shank 37 provided with a conical shaped head 38 at its lower end and with an enlarged annular flanged head 39 at its upper end. 55 The shank 37 of said valve 36 has a loose fit in a bore 40 formed in a bronze bushing 41, and the latter has a drive fit in a bore 42 formed in the spud 13. The bushing 41 has a conical valve seat 43 formed therein fitting the valve head 38 of the 60 valve 36 when in its closed position. A valve port 44 is provided in said bushing 41, axially thereof, to conduct gas from the storage container 10 to the outlet duct 33 through the valve chamber 45 formed by said bores 40 and 42 formed in the 65 bushing 41 and the spud 13 respectively.

A valve crown 50 comprising a screw-plug 51 has screw-threaded engagement in a tapped bore 52 formed in said spud 13 in axial alignment with the vertically disposed valve 36. A copper diaphragm 53 is held in sealed engagement transversely across said bore 52 against an annular seat 54 at the base of said bore 52, by the impingement of the annular rim 55, formed in the base of said screw-plug 51, against the peripheral 70 edge of said diaphragm. A steel button 56 recip-

rocally fits in a suitable bore 57, axially formed in said screw-plug 51. Said button 56 comprises an annular flanged head 58 and a cylindrical stem 59 integral therewith. A set-screw 60, of ordinary construction, has adjustable screw-threaded fit 5 axially in the said screw-plug 51, and impinges upon the upper stem end of said button 56. The button head 58 impinges against the diaphragm 53, centrally thereof, and said diaphragm 53 in turn impinges against the flanged upper end of 10 said valve 36 when said set-screw 60 is screwed inwardly sufficiently to close said valve 36 against its seat 43. For the purpose of releasing gas from the container 10 the valve 36 is opened about from one to two thousandths of an inch, which is accomplished by a slight outward turn of said set-screw 60, the valve 36 being pushed open by the 15 gas pressure in the container.

Each of said bronze bushings 41 is preferably formed in an automatic screw making machine 20 and is provided with a screw-threaded extension 61, integral therewith at its lower end. The main valve M is further provided with an ordinary type of check-valve 62, in removable screw-threaded connection, at 63, with the said lower screw-threaded extension end 61 of said bushing 41. The check-valve 62, herein shown, comprises the valve-housing 64, ball check-valve 65, valve seat 66, valve port 67, and a helical spring 68 of pre-determined design to urge the ball check-valve 30 against its seat.

The operation of the container 10 shown in Figures 1 to 4 inclusive, is as follows:—

The top-head or "combination spud" 13 is removed by withdrawal from the container 10 35 when it is desired to charge the container with "dry ice", or carbon dioxide ice, by first removing the sealing wire 25 and the retaining nuts 18 from the bolts 15. The container is then thoroughly cleaned, if it has been charged previously, and all residue from the previous charge is removed. A bag 70, preferably of light weight canvas or other fabric, filled with activated carbon charcoal, 12', herein termed a cartridge 12, and designed to nicely fit into the container 10 40 is installed, as shown in Figure 1, in the container 10 together with one or more cylindrical blocks 11, of "dry ice" or solid carbon dioxide. The bag 12 may be installed at the bottom below the "ice" block 11 or at the top, above the "ice" 45 50 or in an intermediate position between blocks 11 thereof in the container. Next the "combination spud" 13 is bolted back tight in place, closing the top open end 16 of the container 10, and the nuts 18 are sealed against unauthorized removal by means of said wire 25 and seal 26, interconnecting the bolts 15 as above described. Valves M and R are tightly closed and also the cap 35 normally closing the discharge outlet connection 34, is screwed back tightly in place 55 60 thereon.

Instead of charging the container 10 with so-called "dry ice" it may, of course, be charged with any of the ordinary gases commonly stored under high pressure in the usual present day 65 high pressure cylindrical drums,—in which case the gas to be stored in the container 10 is forced therein through the connection 34, the cap 35 first having been removed and one or both of the valves M and R opened, whereby the "combination spud" 13 does not have to be removed except for occasional inspection and cleaning purposes. After charging the container 10 with a gas under high pressure,—but not in solid 70 form,—the valves M and R are tightly closed 75

and screw-cap 35 is replaced closing the connecting duct 34.

In using my improved high pressure container 10, the operator first removes the screw cap 35 and connects the container 10 with his specific casks, tanks, devices, apparatus or systems requiring gas pressure to operate the same, through usual pipe connections with said discharge outlet connection 34.

10 Next, the operator or user opens the main valve M, on the "combination spud" 13. The ball check-valve 65 is set to open at any pressure desired above, say for example, 150 pounds per square inch by selecting and installing a spring 68 of predetermined, suitable design, and said ball check-valve 65 remains closed, under all pressures below 150 pounds pressure, by the urging pressure of said spring against the valve.

When the pressure of the gas in container 10 falls to the set pressure of 150 pounds of the check-valve 65, the check-valve 65 closes and the gas stops flowing from the container 10, stopping the functions which it performs for the user.

The user then orders a new or fully charged container 10 from his distributor, as he has had warning that his gas pressure is about exhausted in his present container. Next the user opens the reserve valve R on "combination spud" 13, which results in gas flowing (below said 150 pounds pressure) from the container 10 to the devices or apparatus in operative connection, until the gas pressure in the container 10 is exhausted by which time the fully charged or new container should have been delivered to the user.

35 Referring to Figures 5 to 8 inclusive,—which show a somewhat modified form of my improved container 10 previously described with reference to Figures 1 to 4 inclusive,—these figures show the "combination spud" 13' as being electrically welded at 80, to the upper end 16' of the high pressure container 10', at the annular joint 19' thereof, whereby the use of the bolts 15 and nuts 16, shown in Figures 1 to 4 inclusive, are dispensed with. The construction and operation 40 of the main and reserve valves M and R respectively are identical to that above described with reference to Figures 1 to 4 inclusive.

45 Referring to Figure 8, a safety fuse-plug 81, comprising a set-screw 82 having a longitudinal bore 83 plugged with an alloy 84, fusible at a predetermined rise of temperature, or rupturable at a predetermined rise of pressure in the container 10', has a screw-threaded fit in the spud 13', in a threaded bore 85 formed therein 50 for the purpose of excess pressure relief in the container 10'.

55 Referring again to Figures 1 to 4 inclusive, it is well known that solid carbon dioxide, or "dry ice" when reverting into a liquid, expands 60 and needs to occupy considerably more space within a container. Therefore, it is necessary, in order to avoid excessive cylinder wall pressure, to allow a void space within the container of from 30% to 40% depending upon the density 65 or solidity of the dry ice. In order to increase this holding capacity of the container 10 and take care of the expansion, I fill this space, which is unoccupied by the charge 11 of dry ice,—in other words, the void space,—with activated carbon 70 charcoal 12', preferably contained in a mesh bag 12. The porosity of the carbon charcoal being from 80% to 90% and its cellular structure having the property of absorbing carbon dioxide gas in great quantities even up to 35 75 volumes of gas to one of carbon. The using of

an aggregate of dry ice and activated carbon within a container for holding liquid or solid carbon dioxide is new.

The using of a predetermined quantity charge of these materials, either in separate charges or 5 mixed, is new. Bags or cartridges 12 of this material are removable from and replaceable into the container 10 and the activated carbon 12' has a further utility of catching and holding organic impurities that may be in the dry ice or solid 10 carbon dioxide. These impurities may be extracted and removed from the container 10 upon removing the charge of activated carbon 12'. This load or charge of solid carbon dioxide 11, prepared in a predetermined quantity and introduced into a portable shipping container 10, through a removable head 13, is new. An amazing amount of carbon dioxide gas is confined in one pound of solid carbon dioxide. When vaporized, a briquette 1" thick by 5" square, equaling one pound avoirdupois, will produce 10 cubic feet of gas at atmospheric pressure. Therefore the gas released from my retort or container 10 may be used for dynamic propelling power to operate water lifts, dry pipe sprinkler systems, 25 displacing fluids from casks, beer barrels, lifting jacks, nullifying explosive mixtures in pipe lines and tanks, and the like purposes.

While I have herein shown my device in the preferred forms, it will be obvious that changes 30 and modifications may be made in the structures disclosed without departing from the spirit or scope of the invention defined in the following claims.

What I claim as new and desire to secure by 35 Letters Patent is:—

1. A portable shipping container, for storing, transporting and dispensing fluids under high pressure, comprising a cylinder closed at one end thereof, a closure-head affixed to the other end 40 of the cylinder, a discharge outlet connection for said container in said closure-head, an automatic spring-controlled main valve in said closure head arranged to permit the dispensing of fluid at pressures above a fixed minimum reserve pressure 45 in the container, and another hand-operated reserve valve, in said closure-head for dispensing fluid, when manually opened, at the residual pressures below the fixed minimum reserve pressure in the container, and a common discharge 50 outlet duct in said closure-head connecting the said valves with the said common discharge outlet connection.

2. A portable shipping container for storing, 55 transporting, and dispensing fluids under high pressure, comprising the combination of a cylinder closed at one end thereof, a closure-head affixed to the other end of the cylinder, a discharge outlet connection for said container in said closure-head, a combined hand-operated 60 valve and an automatic spring-controlled main valve in said closure head arranged when manually opened, to permit the dispensing of fluid at pressures above a fixed minimum reserve pressure in the container, and another hand-operated 65 reserve valve, in said closure-head for dispensing fluid, when manually opened, at the residual pressures below the fixed minimum reserve pressure in the container, and a common discharge outlet duct in said closure head connecting the 70 said valves with the said common discharge outlet connection.

3. A portable shipping container for storing, 75 transporting and dispensing fluids under high pressure, comprising the combination of a cylin-

der closed at one end thereof, a closure-head affixed to the other end of the cylinder, a discharge outlet for said container, arranged in operative connection therewith, an automatic 5 spring-controlled main valve in operative connection with the said discharge outlet of said container arranged to permit the dispensing of fluid at pressures above a fixed minimum reserve pressure in the container, another hand-operated 10 reserve valve, arranged in operative connection with the said discharge outlet of said container for dispensing fluid, when manually opened, at the residual pressures below the fixed minimum reserve pressure in the container, and a common 15 discharge outlet duct in operative connection with the said discharge outlet of said container connecting the said valves with the said common discharge outlet duct, all substantially as is shown and described herein.

20 4. A portable shipping container for storing, transporting and dispensing fluids under high pressure, comprising the combination of a cylinder closed at one end thereof, a closure-head affixed to the other end of the cylinder, a discharge 25 outlet for said container, arranged in operative duct connection therewith, an automatic spring-controlled main valve, having its duct connection controlled by a hand-operated screw-valve and automatically operated by the pressure of gas 30 when above a certain minimum pressure, in operative duct connection with the said discharge outlet of said container arranged, when said hand-operated screw-valve is manually opened, to permit the dispensing of fluid at pressures 35 above a fixed minimum reserve pressure in the container, another hand-operated reserve valve, also in operative duct connection with the said discharge outlet of said container, for dispensing

fluid, when manually opened, at the residual pressures below the fixed minimum reserve pressure in the container, and a common discharge outlet in operative duct connection with the said discharge outlet of said container connecting the 5 said valves with the said common discharge outlet.

5. A portable shipping container for storing, transporting and dispensing fluids under high pressure, comprising the combination of a cylinder closed at one end thereof, a closure-head affixed to the other end of the cylinder, a discharge outlet for said container, arranged in operative duct connection therewith, an automatic spring-controlled main valve automatically 10 operated by the pressure of gas, when above a certain minimum pressure, in operative duct connection with the said discharge outlet of said container, having its duct connection controlled by a hand-operated screw-valve, arranged, when 20 said hand-operated screw-valve is manually opened, to permit the dispensing of fluid at pressures above a fixed minimum reserve pressure in the container, another hand-operated reserve valve, also in operative duct connection with the 25 said discharge outlet of said container, for dispensing fluid, when manually opened, at the residual pressures below the fixed minimum reserve pressure in the container, a common discharge outlet in operative duct connection with the 30 said discharge outlet of said container connecting the said valves with the said common discharge outlet, and a safety blow-off frangible sealing means, having a bursting pressure below that of the container, arranged in operative discharge outlet duct connection with the said container.

PERCY C. AVERY.
